C. F. BROWN.
PISTON VALVE FOR LIQUID MEASURING APPARATUS.
APPLICATION FILED FEB. 19, 1915.

1,162,562.

Patented Nov. 30, 1915.

UNITED STATES PATENT OFFICE.

CHARLES F. BROWN, OF NEW YORK, N. Y., ASSIGNOR TO UNIVERSAL LIQUID REGISTER COMPANY, OF NEW YORK, N. Y., A CORPORATION OF NEW YORK.

PISTON-VALVE FOR LIQUID-MEASURING APPARATUS.

1,162,562.

Specification of Letters Patent.

Patented Nov. 30, 1915.

Application filed February 19, 1915. Serial No. 9,340.

To all whom it may concern:

Be it known that I, CHARLES F. BROWN, a citizen of the United States, residing at New York, in the county of New York and 5 State of New York, have invented certain new and useful Improvements in Piston-Valves for Liquid-Measuring Apparatus; and I hereby declare that the following is a full, clear, and exact description thereof, 10 reference being had to the accompanying drawings, which form part of this specification.

This invention is a novel improvement in the pistons of liquid measuring apparatus 15 of the type shown in my application for patent Serial No. 807,911, filed December 20, 1913; such apparatus comprising essentially a preferably cylindrical vessel and means whereby liquid can be admitted into either 20 end of the vessel as it is being withdrawn from the other, direct communication within the vessel between the opposite ends thereof being cut off by means of a piston which moves back and forth in the vessel 25 according to the flow of fluid therein.

The present invention has especial relation to such pistons, and its object is to construct such pistons so that they will effectually prevent communication between the 30 interior portions of the vessel at opposite sides of the piston and prevent leakage of fluid therepast, and will also close the outlet ports in the ends of the vessel when they reach the ends of the vessel.

35 I will describe the invention in connection with the accompanying drawings in which—

Figure 1 represents a diagrammatical sectional elevation of a measuring apparatus 40 with my novel piston therein. Fig. 2 is an enlarged sectional view of the piston detached. Fig. 3 is an end view of the piston.

The measuring apparatus comprises a preferably cylindrical vessel 1, closed at its 45 ends by heads 1^a and 1^b; head 1^a being provided with a central port 1^c, and head 1^b with a central port 1^d, to which ports are connected pipes 2^a, 2^b, which are respectively connected at their outer ends to ports 2^e, 2^f, 50 of a four-way valve casing 2 which is also provided with a port 2^g communicating with a supply pipe 4; and with a port 2^h communicating with a pipe 6 connected to a dispensing faucet 6^a which can be operated 55 manually by a handle 6^b.

In the valve casing 2 is a valve 2^h having a stem 2^o to which is connected a handle by which the valve can be manually operated. The valve 2^h has two transverse ports 2ⁱ, 2^k which are so formed that when the valve is 60 in one position port 2ⁱ will establish communication between the ports 2^e and 2^f; and simultaneously port 2^k will establish communication between the ports 2^a and 2^b (as illustrated in full lines in Fig. 1.) By turning the valve to the position indicated in dotted lines in Fig. 1, port 2ⁱ will establish communication between the ports 2^e and 2^f; and port 2^k will establish communication between the ports 2^a and 2^b. The pipe 4 70 communicates with a supply valve 4^a which preferably has two inlet ports connected by pipes 4^b, 4^c to two containers K, K'; and by properly shifting valve 4^a communication can be established alternately between the 75 pipe 4 and either container K or K'.

The vessel 1 is made of such size that it will contain a predetermined quantity of liquid, say one pint or one quart, and the introduction of such a quantity of liquid 80 into the cylinder will force the piston to one end thereof.

The parts thus far described are similar to those shown and described in my afore- 85 said application.

Within the vessel 1 is a novel piston which is movable longitudinally of the cylinder and is adapted to be moved by the liquid admitted into the cylinder as hereinafter explained. This piston forms the subject-matter of the present invention and is constructed as follows: An annular body 7, preferably made of hard rubber and slightly less in external diameter than the interior of the vessel 1, is interposed between oppositely 95 facing cup leathers or washers 7^a whose peripheral flanges are adapted to fit closely against the circular inner wall of the vessel 1. The body and cup washers are strung upon an axial member 8, which is preferably 100 tubular and is exteriorly threaded on its outer ends for engagement of nuts 8^a which clamp the cup leathers firmly against the body; flat ring washers 7^b are preferably strung on the axial member 8 between the 105 nuts 8^a and the washers. Detachably attached to the ends of the axial member 8 are cushions 8^d, preferably formed of rubber or other suitable yieldable or resilient material. These cushions 8^d may be spaced apart by a 110

filler 8^e within the sleeve 8 and are secured in position by means of nuts 8^b screwed on the member 8 and provided with inwardly projecting flanges 8^c on their outer ends 5 whose internal diameter is slightly larger than the external diameter of the nipples 1^h surrounding the inner ends of the ports 1^c, 1^d of the vessel.

The operation of the apparatus is as follows: If the valve 2^h is in the position shown 10 in Fig. 1, and the faucet 6^a be opened; liquid will flow from the container K through pipe 4^b, valve 4^a, pipe 4, port 2^j, pipe 2^a and port 1^c into the vessel 1, and the liquid will force 15 the piston 7 in said vessel toward the head 1^b thereof; and at the same time the liquid contained in the vessel between the piston 7 and head 1^b will be discharged through the port 1^d, pipe 2^b, port 2^k, pipe 6, and faucet 20 6^a. When the piston 7 moves against the head 1^b (as indicated in dotted lines in Fig. 1) its cushion 8^d closes the port 1^d and no more liquid escapes through the faucet; and 25 no more liquid can enter the measuring vessel 1 through port 1^h. When no more liquid escapes through the pipe 6, valve 2^a may be shifted so as to establish communication between pipes 4 and 2^b; and between pipes 2^a and 6 (as indicated in dotted lines in Fig. 30 1,) and then if the faucet 6^a be opened, liquid will flow from the supply through pipes 4 and 2^b into the vessel 1 through port 1^d and force piston 7 to the left; and liquid will be discharged through the port 1^c and 35 pipes 2^a and 6 until the piston reaches the head 1^a of the vessel, and port 1^c is closed by the adjacent cushion 8^d on the piston 7; then no more liquid will escape through pipe 6, until the valve 2^h is again shifted to the 40 position shown in full lines in Fig. 1. By shifting the valve 2^h communication is established alternately between the supply and the opposite ends of the vessel 1, and between the opposite ends of said vessel and 45 the faucet; but at no time can direct communication be established between the supply and the faucet.

It will be seen that when pressure is 50 brought to bear against the cup leathers from either end of the vessel it presses the lips or flanges of such cup leathers outward against the walls of the vessel, and the harder the pressure the more certainly will the piston eliminate the air or gas in the 55 vessel, and prevent passage of gas or liquid past the piston from one end of the vessel to the other. My piston overcomes the difficulties which have been experienced with the pistons formerly used in such vessels, owing to the fact that the drawn tubing 60

(from which the vessel is ordinarily made) will always vary somewhat in diameter owing to uneven contraction in cooling off. But by the use of my piston an even measure is always delivered from each end of the vessel. The flanged nuts 8^b hold the cushions 8^d truly against the ends of the filler block 8^e in the axial member 8, thus insuring 65 that the cushions will perfectly seal the ports in the ends of the cylinder. When the 70 filler 8^e is loosely fitted in the member 8 it permits pressure to be transmitted directly through the filler from one cushion to the other.

The cup leathers preferably have lips of 75 about one-half inch in length and will last for years without replacing same, as they will wear principally from the ends, whereas a flat washer placed around the circumference of a piston head will wear off and 80 become smaller by the constant friction and will require frequent replacing.

What I claim is:

1. A piston comprising a tubular axial member, an annular body strung on said member, oppositely facing cup leathers on 85 said axial member at opposite sides of the body member, and resilient cushions detachably attached to opposite ends of the axial member. 90

2. A piston comprising a tubular axial member having threaded ends, an annular body strung on said axial member, oppositely facing cup leathers on said axial member at opposite sides of the body, resilient 95 cushions at opposite ends of the axial member, flanged nuts screwed on the ends of the body member and holding said cushions in position, and a filler in the tubular axial member interposed between said cushions. 100

3. A piston for the purpose specified, comprising an axial member, a body member on said axial member, oppositely facing cup leathers strung on said axial member at opposite sides of the body member, means on 105 the axial member for clamping the cup leathers to the body member, cushion members at the opposite ends of the axial member, and annular flanged nuts screwed on the ends of the axial member and holding 110 said cushion members in position, substantially as described.

In testimony that I claim the foregoing as my own, I affix my signature in presence of two witnesses.

CHARLES F. BROWN.
